CHARLES GOOCH, OF CINCINNATI, OHIO.

Letters Patent No. 64,304, dated April 30, 1867.

IMPROVEMENT IN SKATES.

The Schedule referred to in these Letters Patent and making part of the same.

TO ALL WHOM IT MAY CONCERN:

Be it known that I, CHARLES GOOCH, of Cincinnati, Hamilton county, Ohio, have invented a new and useful Improvement in Skates; and I do hereby declare that the following is a full, clear, and exact description thereof, which will enable others skilled in the art to make and use the same, reference being had to the accompanying drawings, forming part of this specification.

The present invention relates to clamps for securing skates to the soles of boots and shoes, which clamps are of such a construction that they can be readily applied and adapted to any of the ordinary wooden-frame skates which are provided with straps for strapping them to the foot of the wearer. In the accompanying drawings my improvement in skates is illustrated—

Figure 1 being a plan view of the under side of a skate having my clamps applied thereto.

Figure 2, a side view of the same.

Figures 3 and 4, transverse vertical sections taken in the planes of the respective lines xx and yy , fig. 1; and Figure 5, a detail view on an enlarged scale of one of the clamps.

Similar letters of reference indicate corresponding parts.

A, in the drawings, represents the ordinary wooden frame or foot-rest of a skate, which, at or near its front and rear ends, is provided with the usual rectangular-shaped holes B to receive the straps that are commonly employed for strapping a skate to a boot or shoe. C, the runner or blade to the skate. D, my improved clamps, which are made in two parts or sections, E, each of which consists of a flat plate, F, of suitable size and shape to fit in the holes B of the foot-rest A, and provided with an upright arm, G, having a prong or prongs, H, at one of its ends. I, a bolt connecting the two parts E together, to one of which it is secured, while through the other it loosely extends and is provided with a thumb-nut, J, at its outer end, by the turning of which, either to the right or left, the two parts of the clamp are caused to be either drawn toward or moved away from each other, as the case may be, whereby, as is obvious, their pronged arms G may be made to embed themselves in the sides of the sole of the boot or shoe, and thus to secure the skate firmly thereto. By my improved clamp, when so desired, they can be detached from the skates, and are in fact entirely independent thereof, requiring no alteration in the skate-rest, but leaving it free to be used with straps, as before.

I claim as new, and desire to secure by Letters Patent—

The clamp D, fitting in the holes B of the foot-rest A, consisting of the plates F with inclined inner edges, and having pronged upright arms G, and adjusted by means of the bolt I and thumb-nut J, as herein set forth for the purpose specified.

The above specification of my invention signed by me this 5th day of January, 1867.

CHARLES GOOCH.
